3 Claims. (Cl. 257—2)

This invention relates to improvements in the utilization of the waste heat of condensates and to apparatus to be employed in connection therewith.

5 In connection with the utilization of the heat available from the condensate obtained in super-heated steam installations, it has always been the rule hitherto that the condensate should first be relieved of pressure and then passed into a
10 heat exchanger, at the temperature corresponding to the resulting reduced pressure. The object of thus initially relieving the pressure is to prevent the occurrence, within the heat exchanger, of a sudden disengagement of steam
15 giving rise to sudden knocks or shocks which are liable to cause damage to the heat exchanger. On the other hand, this method is attended with the serious drawback that only the lower portion of the temperature drop is utilized for heat ex-
20 changing purposes, whereas the high tempera-
ture drop which is the most valuable part as regards heat exchange, is wasted.

The main object of the present invention is to enable the waste heat of the condensate from
25 heating plants to be substantially completely utilized in a heat exchanger, while avoiding previous release of the pressure. In this manner a more efficient utilization of the heat of the condensate is brought about, whilst, at the same
30 time, the liquid to be heated in the heat ex-
changer is raised to a higher temperature than hitherto possible.

The invention is based on the general conception that any substantial release of pressure of
35 the condensate within the heat exchanger—which is the cause of the sudden disengagement of steam with the ensuing circulation troubles—may be prevented, and the initial high pressure of the condensate thus substantially maintained
40 in the heat exchanger by the provision of a pressure check device on the exit side of the heat exchanger. In this manner the release of pressure of the condensate is not effected until it has left the heat exchanger and the troubles
45 heretofore encountered are avoided. According to the invention the said pressure check device is preferably controlled by the level of the con-
densed liquid in the receiver or tank provided for supplying the heat exchanger with liquid,
50 the device being, for example, actuated directly by a float provided in the vessel receiving the condensate. When operating in this manner it is advantageous that the vessel for receiving the condensate issuing from the heat exchanger, the
55 pressure upon which is to be thereupon released,

should be located immediately adjoining the first receiver and separated therefrom merely by a partition.

In order more clearly to understand the invention, reference is made to the accompanying drawing, which illustrates diagrammatically and by way of example, one embodiment of apparatus suitable for carrying the method of the present invention into practical effect.

In said drawing, which represents an elevation partly in section of the apparatus, the receiver I is shown provided with a closed float Sch, but there is nothing to prevent an open-float type from being used. The condensate first enters the receiver I, by way of pipe line S₁, and issues through pipe line S₂ into the heat exchanger A, through which it flows—giving up its heat—in the direction of the arrow, and passes off in a state of lower temperature, but still under pressure. It next reaches the receiver II, by way of pipe line S₃ and, after the pressure has been released, in passing through the control device O—in this case the valve controlled by the float Sch—is allowed to escape into the outside through pipe S₄.

The receiver I is separated from the receiver II solely by the partition W, through which is passed, axle D of the control device O which is actuated by float Sch through lever or rod G. When the flow of condensate decreases, with ensuing lowering of the level of the condensate in the vessel I, the float also sinks and throttles the outflow of condensate from the vessel II, by actuating the shut-off member O. The pressure in the vessel I is approximately equal to that in the heating plant from which the condensate is derived. The pressure in vessel II is only slightly lower, namely by the amount corresponding to the unavoidable pressure drop of the condensate sustained during its passage through the heat exchanger. Since the difference of pressure in the vessels I and II is thus only slight, even in the case of large quantities of condensate, a simple packing is sufficient for the rod in its passage through the partition W, no special stuff-
ing box being required.

I claim:

1. A device for the utilization of heat of waste condensates comprising a vessel for receiving the condensate at its initial pressure, a heat ex-
50 changer in pressure communication with said vessel, a pressure check device located at the exit side of the condensate from such heat exchanger adapted to reduce the pressure of said condensate, and means for controlling the flow of said
55

condensate through said pressure check device so as to render it commensurate with the supply of condensate to said receiving vessel.

2. A device for the utilization of heat of waste condensates comprising a vessel for receiving the condensate at its initial pressure, a float in said vessel, a heat exchanger in pressure communication with said vessel, a pressure-check device located at the exit side of the condensate from such heat exchanger and adapted to reduce the pressure of said condensate, means for controlling the flow of said condensate through said pressure-check device, said means being actuated by said float in said receiving vessel in such a manner as to render the outflow of condensate from said heat exchanger commensurate with the supply of condensate to said receiving vessel.

3. A device for the utilization of heat of waste condensates comprising a vessel for receiving the condensate at its initial pressure, a float in said vessel, a heat exchanger in pressure communication with said vessel, a pressure-check device adapted to reduce the pressure of said condensate and located at the exit side of the condensate from such heat exchanger and adjacent said receiving vessel, means for controlling the flow of said condensate through said pressure-check device, said means being actuated by said float in said receiving vessel in such a manner as to render the outflow of condensate from said heat exchanger commensurate with the supply of condensate to said receiving vessel.
